UNITED STATES PATENT OFFICE

141,349

DESIGN FOR A COMBINED SWING SPOUT AND ESCUTCHEON FOR MIXING FAUCETS

Jacques Stanitz, Warren, Ohio, assignor to Mullins Manufacturing Corporation, Salem, Ohio, a corporation of New York

Application March 2, 1945, Serial No. 118,216

Term of patent 7 years

(Cl. D91—3)

To all whom it may concern:

Be it known that I, Jacques Stanitz, a citizen of the United States, residing at Warren, in the county of Trumbull and State of Ohio, have invented a new, original, and ornamental Design for a Combined Swing Spout and Escutcheon for Mixing Faucets, of which the following is a specification, reference being had to the accompanying drawing forming part thereof.

Figure 1 is a top plan view of a combined swing

spout and escutcheon for mixing faucets showing my new design;

Fig. 2 is a front elevation thereof; and

Fig. 3 is a side elevation thereof.

I claim:

The ornamental design for a combined swing spout and escutcheon for mixing faucets, substantially as shown.

JACQUES STANITZ.
